(57) **CLAIM**

The ornamental design for a display for a vehicle door, as shown and described.

DESCRIPTION

FIG. 1 is a front perspective view of a display for a vehicle door according to the design;
FIG. 2 is a front elevation view thereof;
FIG. 3 is a back elevation view thereof;
FIG. 4 is a right side elevation view thereof;
FIG. 5 is a left side elevation view thereof;
FIG. 6 is a top plan view thereof;
FIG. 7 is a bottom plan view thereof; and,
FIG. 8 is a back perspective view thereof.

The broken lines in the drawings illustrate portions of the display for a vehicle door that form no part of the claimed design.
